HAIR COMB

Fannie Price, New York, N. Y.

Substituted for abandoned application Serial No. 453,148, August 1, 1942. This application June 19, 1945, Serial No. 600,259

4 Claims. (Cl. 132—16)

This invention relates to new and useful improvements in a hair comb. This is a substitute for my abandoned application filed August 1, 1942, Serial Number 453,148.

More particularly, the invention contemplates the construction of an article as mentioned which is adapted to have coarse teeth, medium teeth or fine teeth, as desired.

More specifically, it is proposed that the article have one set of teeth which may be turned to various positions so that when the hair comb is used the effect is substantially the same as if the coarseness of the teeth were changed.

Still further the invention proposes a construction as previously mentioned which may be adapted to various designs and constructions of hair combs.

Another object of the invention is the construction of a device as mentioned which is simple and durable and which may be manufactured and sold at a reasonable cost.

For further comprehension of the invention, and of the objects and advantages thereof, reference will be had to the following description and accompanying drawing, and to the appended claims in which the various novel features of the invention are more particularly set forth.

In the accompanying drawing forming a material part of this disclosure:

Fig. 1 is a side elevational view of a combination hair comb and brush constructed in accordance with this invention.

Fig. 2 is a top plan view of Fig. 1.

Fig. 3 is an end elevational view looking in the direction of the line 3—3 of Fig. 1.

Fig. 4 is a fragmentary horizontal sectional view taken on the line 4—4 of Fig. 1.

Fig. 5 is a vertical sectional view taken on the line 5—5 of Fig. 4.

Fig. 6 is a fragmentary bottom view looking in the direction of the line 6—6 of Fig. 1.

Fig. 7 is a fragmentary bottom view similar to Fig. 5 but illustrated with the teeth in a different position.

Fig. 8 is a perspective view of one of the teeth per se.

Fig. 9 is a side elevational view of another embodiment of a comb and brush constructed in accordance with the same invention.

Fig. 10 is another perspective view of another comb and brush constructed in accordance with the same invention.

The hair comb and brush, in accordance with this invention, includes a back 10 having a side portion 11 releasably held in position with several

fastening elements 12, such as screws. The back 10 has a groove 13 extended in from the bottom immediately adjacent said removable side portion 11. A plurality of flat comb teeth 14 extend along the bottom of said back 10. Each comb tooth has an enlarged top portion 15 engaged in the said groove 13 and a blade portion 16. A plurality of brush bristles 17 are mounted upon the top of the back 10. The back 10 is also provided with a handle 18 by which the comb or the brush may be conveniently manipulated.

Means is provided for flexibly holding the top portions 15 of the comb teeth 14 to normally hold the teeth transversely of the back 10. This means 15 includes an elastic strap 19 having each end 19a fixedly attached to one of the ends of the groove 13. The elastic strap 19 extends across the complete length of the groove 13. Each top portion 15 is formed with a slot 20 through which the elastic strap 19 passes.

Serrations 21 are formed along one of the sides of each top portion 15 and are cooperative with complementary serrations 22 formed upon the inner face of the removable side portion 11 of the back 10. A pad or other friction strip 23, preferably, is extended along the side of the groove 13 which is opposed to the removable side portion 11.

When the fastening elements 12 are loosened, the top portions 15 are free to turn and will be turned by the elastic strip 19 so that the blades 16 are transversely of the back 10 as illustrated in Fig. 5. The fastening elements 12 may now be tightened so that the serrations 22 grip the serrations 21 and force the top portions 15 tightly against the friction pad 23 to hold the teeth from turning. The comb may now be used, and if the teeth are fine teeth, the comb will function as a fine comb.

If desired, the fastening elements 12 may be loosened slightly and each tooth blade 16 turned to a desirable angular position, for example, as illustrated in Fig. 6. Each top portion 15 will be held against turning back by the inter-engagement of the serrations 21 and 22 and the action of the pad 23. The fastening elements 12 may then be turned tight to fixedly hold each of the comb teeth in its new angular position. The comb, when now used, will have the effect of a comb capable of better smoothing the hair since the distance between the teeth has been changed in a way to increase the frictional resistance of the passage of the hair between the teeth.

In Fig. 9 another comb and brush has been illustrated constructed in accordance with the same invention. It is provided with a back 10'

having a removable side portion 11'. It is also provided with the flat comb teeth 14, projecting from one side of the back 10', and bristles 17' mounted upon another side of the back 10'. In other respects this form of the invention is identical to the prior form and like parts are identified by similar reference numerals.

In Fig. 10 still another form of the invention is disclosed in which the combination comb and brush includes a back 10'' having a removable side portion 11'' and flat comb teeth 14 mounted upon one side of the back. Bristles 17'' are mounted upon the other side of the back. In other respects this form of the invention is similar to the previous forms.

While I have illustrated and described the preferred embodiments of my invention, it is to be understood that I do not limit myself to the precise constructions herein disclosed and the right is reserved to all changes and modifications coming within the scope of the invention as defined in the appended claims.

Having thus described my invention, what I claim as new, and desire to secure by United States Letters Patent is:

1. In an article of the class described, a back having a side portion releasably held in position and having a groove extended in from the bottom adjacent said side portion, and flat comb teeth extending along the bottom of said back, each comb tooth having an enlarged base engaged in said groove, means for flexibly holding said bases to hold said teeth transversely of said back, and means for fixedly holding said comb teeth in selected turned positions.

2. In an article of the class described, a back having a side portion releasably held in position and having a groove extended in from the bottom adjacent said side portion, and flat comb teeth

extending along the bottom of said back, each comb tooth having an enlarged base engaged in said groove, means for flexibly holding said bases to hold said teeth transversely of said back, and means for fixedly holding said comb teeth in selected turned positions, said means for flexibly holding said bases including a resilient strip mounted across the ends of said groove and extending through slots in said bases.

3. In an article of the class described, a back having a side portion releasably held in position and having a groove extended in from the bottom adjacent said side portion, and flat comb teeth extending along the bottom of said back, each comb tooth having an enlarged base engaged in said groove, means for flexibly holding said bases to hold said teeth transversely of said back, and means for fixedly holding said comb teeth in selected turned positions, comprising serrations on one of the sides of said bases engaging complementary serrations on the inner side of said portion.

4. In an article of the class described, a back having a side portion releasably held in position and having a groove extended in from the bottom adjacent said side portion, and flat comb teeth extending along the bottom of said back, each comb tooth having an enlarged base engaged in said groove, means for flexibly holding said bases to hold said teeth transversely of said back, and means for fixedly holding said comb teeth in selected turned positions, comprising serrations on one of the sides of said bases engaging complementary serrations on the inner side of said side portion, and a pad extended along the other side of said groove and engaging against said bases.

FANNIE PRICE.
